UNITED STATES PATENT OFFICE.

JOHN A. JACKSON, OF CHICAGO, ILLINOIS, ASSIGNOR OF ONE-HALF TO DEXTER L. PHIPPS, OF CHICAGO, ILLINOIS.

COUPLING-CUSHION BUFFER.

1,002,062.

Specification of Letters Patent. Patented Aug. 29, 1911.

Application filed December 16, 1907. Serial No. 496,738.

To all whom it may concern:

Be it known that I, JOHN A. JACKSON, a citizen of the United States of America, residing at Chicago, in the county of Cook and State of Illinois, have invented certain new and useful Improvements in Coupler-Cushion Buffers, of which the following is a specification, reference being had therein to the accompanying drawings.

10 In standard railway car construction, the draft rigging is supported by draft timbers which are secured against the underside of the longitudinal sills and otherwise, and the motion of the draw-bar is retarded by shock absorbing devices contained in the rigging. The shocks transmitted to the sills have a transverse shearing action thereon due to the position of the rigging which in time disrupts the car frame. 15 The draw-bar head is provided with a safety horn or lug which when the shock devices have gone to their limit under severe and unusual blows, contacts or backs against a solid block or buffer secured 20 against the end sill in horizontal alignment with the longitudinal sills, thereby imparting a direct blow without cushioning to the car body.

This invention relates to a coupler cushion buffer whereby the extreme shocks which the draft rigging ordinarily has to withstand and transmit in an oblique line to the sills are taken up by members whose thrust is in the plane of and directly against the 25 end of the sills, a positive arrest of the coupler or draw-bar head also being provided for.

The invention consists in the matters hereinafter set forth, and more particularly 30 pointed out in the appended claims.

Referring to the drawings, Figure 1 is a view of an end portion of a car equipped with a standard type of draft rigging and a coupler cushion buffer embodying features 45 of the invention. Fig. 2 is a view in detail in horizontal section through the buffer.

In the drawings, 1 indicates a car body of conventional type, having an end sill 2 and longitudinal main sills 3 with draft timbers 4 secured to the underside of the latter in the usual position. A draw bar 5 of standard design supported by any conventional

manner to the draft timbers has a standard head or coupler 6 with the conventional safety horn or lug 7 in the horizontal plane 55 of the sills.

A metal buffer is secured by suitable means, as bolts 8, against the end sill 2 in the path of the horn 7. In its preferred form this consists of a rectangular casing 9 having a movable front buffer plate 10 retained by the casing bottom and flanges 11 on the side walls 12. A central triangular or wedge-shaped lug 13 on the plate has sliding engagement with the adjacent faces 65 of a pair of movable triangular friction blocks 14 whose lateral position is defined by the inwardly beveled faces 15 of a pair of wings 16 on the casing walls, and whose longitudinal movement is resisted by a set of 70 transverse leaf or plate springs 17 bearing only against the raised center of the back 75 85 95 18 of the casing with their ends free to move, their forward displacement being prevented by the wings 16. A suitable cover 19 is removably secured on the casing.

The buffer as a whole is so adjusted in relation to the draw-bar and draft rigging as to intercept the horn before the rigging has received extreme shocks beyond its normal 80 90 capacity, the horn being gradually arrested by the combined action of the springs and frictional engagement of the inclined faces of the buffer plate, blocks and wings, and the latter closing on each other to form a 85 solid backing definitely arresting the horn.

The disposition of the wings, springs and friction blocks afford frictional yielding resistance which effectively transmits all impacts of the horn gradually in a straight 90 line to the sills, thereby eliminating the transverse or oblique strains which the underhung draft rigging necessarily imparts to the sills. The rigging can thus be made lighter as it need not have the great range 95 of resistance otherwise required while the cushion buffer occupies only the space usually taken by the solid buffer block.

The main feature is the yielding transmission of extreme shocks from the horn 100 longitudinally to the car sills while the definite arrest of the horn required in standard construction is likewise provided for.

Obviously the construction may be changed

without departing from the spirit of the invention, and I do not limit myself to any particular form or arrangement of parts.

The buffer may be used on steel as well as wooden cars.

What I claim as my invention is:—

1. The combination with the end sills, main sills, and draw bar of a railway car of standard construction, of a coupler cushion buffer in horizontal alinement with the main sills and the draw bar safety horn, consisting of a rectangular metal casing secured to the end sill above the draw bar, having parallel side walls with inwardly turned flanges at their outer ends, a pair of alined wings on the inner faces of the side wall back of and parallel to the end flanges and provided with inwardly beveled bearing faces, a rear wall having a vertical raised central portion, transversely disposed leaf springs whose central portions bear against the raised center of the back and whose outer ends lie behind the side wall wings by which they are prevented from excessive forward movement, a pair of triangular friction blocks whose inner faces normally parallel to the inner margins of the wings bear against the leaf springs and whose outer side faces have sliding frictional engagement with the beveled faces of the wings, and a movable buffer plate whose end portions play between the inturned outer margins of the side walls and the wings and whose center portion has a rearwardly extending wedge shaped lug on its rear face extending between the blocks in frictional sliding engagement with the adjacent faces thereof.
2. In a railway car of standard construction, the combination with the end sills, main sills, draft timbers secured to the underside of the main sills, and a draw-bar yieldingly secured to the draft timbers be-

neath the sills and provided with a safety horn on its coupler head in the horizontal plane of the sills, of a coupler cushion buffer consisting of a substantially rectangular casing secured by its back wall to the outer face of the end sill in alinement with the horn, side and bottom walls integral with the back wall, the back wall having a longitudinally crowned face between the side walls, a pair of oppositely disposed wings integrally formed on the inner faces of the side walls with perpendicular, inwardly beveled friction faces, a set of transverse leaf springs bearing at their center only against the center of the crowned face of the back plate, a pair of triangular friction blocks whose bases bear against the springs and whose outer sides each have frictional sliding engagement with the adjacent friction face of a wing, and a buffer plate movable in the casing between the wings and inwardly turned end flanges on the side walls provided with a central wedge-shaped lug bearing laterally against the inner faces of the friction blocks and abutting the supported center portion of the spring when the plate is in its rearmost position and forcing the blocks along the beveled friction faces of the wings against the yielding unsupported arms of the spring, the blocks bearing against the central supported portions of the spring and sliding outwardly between and in frictional engagement with the yielding spring arms and the side wall wings when moved outwardly by the inward movement of the buffer plate lug.

In testimony whereof I affix my signature in presence of two witnesses.

JOHN A. JACKSON.
